[57] CLAIM

The ornamental design for a foldable playard, as shown and described.

DESCRIPTION

FIG. 1 is a perspective view of a foldable playard showing our new design;

FIG. 2 is a front elevation view;

FIG. 3 is a side elevational view;

FIG. 4 is a top plan view; and

FIG. 5 is a bottom plan view thereof.

FIG. 6 is a perspective view of the foldable playard of FIG. 1 in collapsed position and enclosed by the mat which forms the playard floor in FIG. 1;

FIG. 7 is a front elevational view of the foldable playard of FIG. 6;

FIG. 8 is a rear elevational view of the foldable playard of FIG. 6;

FIG. 9 is a top plan view of the foldable playard of FIG. 6;

FIG. 10 is a bottom plan view of the foldable playard of FIG. 6;

FIG. 11 is a left end view of the foldable playard of FIG. 6; and

FIG. 12 is a right end elevational view thereof.

FIG. 1

FIG. 2

FIG. 3

FIG. 4

FIG. 5

FIG. 6

FIG. 12

FIG. 11

FIG. 7

FIG. 8

FIG. 9

FIG. 10
